UNITED STATES PATENT OFFICE.

ROBERT SMITH, OF GRAND RAPIDS, MICHIGAN, ASSIGNOR, BY DIRECT AND MESNE ASSIGNMENTS, TO HERBERT B. GILLETTE, OF GRAND RAPIDS, MICHIGAN, AND THE MICHIGAN TRUST COMPANY, RECEIVER OF R. G. PETERS MANUFACTURING COMPANY.

MACHINE FOR FINISHING ROLLERS

1,098,336.

Specification of Letters Patent.

Patented May 26, 1914.

Application filed January 25, 1910. Serial No. 540,050.

To all whom it may concern:

Be it known that I, ROBERT SMITH, a citizen of the United States, residing at Grand Rapids, Michigan, have invented 5 certain new and useful Improvements in Machines for Finishing Rollers, of which the following is a specification.

This invention relates to improvements in machines for finishing rollers.

10 My improvements are particularly designed for the finishing of bearing rollers, where it is very desirable that all of the rollers shall be of the same size and that they shall be smoothly finished.

15 The main objects of this invention are: First, to provide an improved machine for use in finishing rollers, which enables the rapid production of substantially perfect bearing rollers. Second, to provide a machine having the above advantages, which is 20 very simple in structure and in operation.

Further objects, and objects relating to structural details will definitely appear from the detailed description to follow.

25 I accomplish the objects of my invention by the devices and means described in the following specification.

The structure described constitutes one effective embodiment of my invention. 30 Other embodiments would be readily devised by those skilled in the art.

The invention is clearly defined and pointed out in the claims.

A structure constituting an effective and 35 preferred embodiment of the features of my invention is clearly illustrated in the accompanying drawing, forming a part of this specification, in which:

Figure 1 is a plan view of a structure embodying the features of my invention. Fig. 2 is a vertical section, taken on a line corresponding to line 2-2 of Fig. 1. Fig. 3 is a detail of the member 12. Fig. 4 is a detail view of the member 13. Fig. 5 is a side 45 elevation of one of the rollers which the structure illustrated is particularly designed to finish. Fig. 6 is a detail view, partially in vertical section, of a modified construction. Fig. 7 is a side elevation of one 50 of the rollers which the machine shown in the modification of Fig. 6 is especially designed for producing. Fig. 8 is an enlarged detail of the finishing member 30.

In the drawing similar reference char-

acters refer to similar parts throughout the 55 several views, and the sectional views are taken looking in the direction of the little arrows at the ends of the section lines.

Referring to the drawing, the support or base 1 is provided with projecting ears 2, 60 adapted to receive the securing bolts 3 by means of which the support is secured upon a table or other suitable bed. The support 1 is provided with an annular seat 4. In this seat 1 I arrange a finishing member 5, 65 preferably a ring having an annular finishing surface 6 adapted to act on one end of the rollers to be finished, as at 8. These rollers illustrated, and for the manufacture of which the embodiment of my invention is 70 especially designed and adapted, are conical, the same being of uniform taper from end to end, and provided with conical small ends 8 and convex large ends 9. (See Fig. 5.) On this member 5, I arrange the finishing 75 member 10 which is preferably a ring having an inclined annular finishing surface 11 thereon adapted to act on the sides of the rollers. I also provide finishing members 12 and 13 for the large ends of the rollers. 80 These finishing members are provided with annular finishing surfaces 14 and 15 respectively, the finishing surface 14 of the member 12 being toothed, while that of the member 13 is smooth, or a polishing surface. 85

The finishing surfaces of the members 12 and 13 are curved in cross section to form the convex ends of the rollers. The finishing surfaces 6 and 11 of the members 5 and 10 are smooth surfaces. These finishing 90 members are formed of steel, preferably of tool steel. A coaxial rotatable finishing member 16 is provided having a conical finishing surface 17, which acts on the sides of the rollers to be finished.

95 A feed member 18 is provided for the finishing members, the feed member being provided with a seat 19 adapted to receive either of the members, or a feed member 18 may be provided for each finishing member, as will 100 be obvious. The member 18 is threaded into the support 1 so that it can be fed downwardly to force the rollers to the finishing members 5, 10 and 16. The member 18 is preferably adjusted by providing the same 105 with a lever 20 having a hole 21 therein adapted to be engaged over the pin 22 on the support 1.

The rotatable member 16 is provided with a driving shaft 23, the driving means not being here illustrated. In the use of the machine, a plurality of master rollers, as 24, 5 are preferably provided, the master rollers being of the size of the finished rollers. These master rollers are preferably made of high speed steel, being of the exact size desired.

In use, the device is filled with rollers which have been formed, as by a screw machine, and the cutting member 12 is inserted in the feed member 18. This is gradually fed down, and as the metal is forced up on 15 the rollers by the finishing members acting on the sides thereof, it is cut or ground off by the cutting member, as 12. The finishing member 13 is then substituted for the cutting member, and the master rollers introduced and the machine operated until the rollers to be finished are smooth and of uniform size. They are then taken from the machine and case hardened. The rollers are then replaced in the machine, along with 20 the master rollers and the polishing or finishing member 13, and the machine operated until the rollers are brought to a nice polish and finish and any irregularity or roughness produced by the case hardening operation 25 removed.

In the modified structure shown in Figs. 6 and 7, the finishing ring or member 25 is beveled off at 26 to accommodate the projecting pin 27 on the roller 28, the roller being 30 slightly modified by having this pin on its small end and by having the beveled edge 29 at its large end.

The cutting ring 30 of this device is provided with a cutting edge 31 instead of being toothed, as shown at 14 in Fig. 3 (see the 40 details of this ring 30 in Fig. 8). In this modified construction the side finishing member 10 is seated directly in the seat 4 instead of resting on the finishing member 45 5, as is the case in the structure shown in Fig. 2, the finishing member 25 being arranged also to rest in the seat 4 within the finishing member 10. The means for feeding the feed member 8 is not shown in this 50 modified construction.

By the aid of this machine I am enabled to very rapidly and economically produce perfect rollers which have a very fine finish throughout.

The machine illustrated is adapted for the 55 finishing of tapered rollers having conical small ends and convex large ends, as shown in the drawing. It is obvious that the structure is adapted to the manufacture of other 60 forms of rollers merely by the changing of the form of the finishing surfaces.

I have illustrated and described my improvements in detail in the form in which I have embodied the same in practice, as I 65 have found this form to be very satisfactory.

I am, however, aware that my invention is capable of considerable change in structural details and embodiments, and I desire to be understood as claiming the same in detail in the form illustrated, as well as broadly 70 within the scope of the appended claims.

Having thus described my invention, what I claim as new and desire to secure by Letters Patent is:

1. The combination with a support having a seat therein, of a finishing member arranged in said seat and having finishing surface adapted to act on one end of the rollers to be finished; a finishing member arranged in said seat and adapted to act on the sides of the rollers to be finished, said side finishing member being provided with a finishing surface of a width corresponding to the length of the bodies of the rollers to be finished; a finishing member having an annular finishing surface thereon adapted to act on the other end of the rollers to be finished; a feed member threaded into said support and having a seat therein adapted to receive the said last mentioned end finishing member; a pivoted lever mounted on said feed member, said support being provided with pins with which said lever is adapted to be engaged; and a rotatable finishing member having a side finishing surface thereon.

2. The combination with a support having a seat therein, of a finishing member arranged in said seat and having finishing surface adapted to act on one end of the rollers to be finished; a finishing member arranged in said seat and adapted to act on the sides of the rollers to be finished, said side finishing member being provided with a finishing surface of a width corresponding to the length of the bodies of the rollers to be finished; a finishing member having an annular finishing surface thereon adapted to act on the other end of the rollers to be finished; a feed member therefor 100 threaded into said support; and a rotatable finishing member having a side finishing surface thereon.

3. The combination with a support having a seat therein, of a finishing member arranged in said seat and having an annular finishing surface adapted to act on the small ends of the rollers to be finished; a side finishing member arranged in said seat, said side finishing member being provided with an annular inclined finishing surface of a width corresponding to the length of the bodies of the rollers to be finished; a finishing member having an annular finishing surface on its lower edge adapted to act on the 115 large ends of the rollers to be finished, said finishing surface being curved in cross section; a feed member therefor threaded into said support; and a rotatable finishing member having a conical finishing surface.

4. The combination with a support having a seat therein, of a finishing member arranged in said seat and having an annular finishing surface adapted to act on the small ends of the rollers to be finished; a finishing member arranged in said seat; an annular side finishing member; a finishing member having an annular finishing surface on its lower edge adapted to act on the large ends of the rollers to be finished, said finishing surface being curved in cross section; and a rotatable member having a conical finishing surface.
5. The combination with a support, of a finishing member having an annular finishing surface adapted to act on one end of the rollers to be finished; a finishing member having an annular inclined finishing surface of a width corresponding to the length of the bodies of the rollers to be finished; a finishing member having an annular finishing surface thereon adapted to act on the other ends of the rollers to be finished, said finishing surface being curved in cross section; a feed member for the last mentioned end finishing member; and a rotatable member having a conical finishing surface.
6. The combination with a support of a finishing member having an annular finishing surface adapted to act on one end of the rollers to be finished; a finishing member having an annular finishing surface adapted to act on the sides of the rollers to be finished; a finishing member having an annular
- finishing surface thereon adapted to act on 35
the other end of the rollers to be finished; an adjustable feed member adapted to receive the last mentioned end finishing member; and a rotatable member having a side finishing surface thereon.
- 40
7. The combination with a support of a finishing member having an annular finishing surface adapted to act on one end of the rollers to be finished; a finishing member having an annular finishing surface adapted 45 to act on the sides of the rollers to be finished; a finishing member having an annular finishing surface thereon adapted to act on the other end of the rollers to be finished; and a rotatable member having a 50 side finishing surface thereon.
8. In a structure of the class described, for manufacturing rollers, the combination of a suitable cone-shaped finishing member; a cup-shaped finishing member corresponding 55 to said cone, one of which members is revolvable; a plurality of master rollers for supporting the said cone and cup in accurate spaced relation, whereby said rollers may be accurately finished at the sides between the 60 same, as specified.

In witness whereof, I have hereunto set my hand and seal in the presence of two witnesses.
